MOBILE SPRAYER

Roy F. Broyhill, Dakota City, Nebr. 68731

Filed Feb. 11, 1972, Ser. No. 225,701

Term of patent 14 years

Int. Cl. D23—01

U.S. Cl. D23—18

FIG. 1 is a perspective rear view of a mobile sprayer showing my new design with a carrier vehicle therefor shown in broken lines for illustration only,

FIG. 2 is another rear perspective view thereof;

FIG. 3 is a front perspective view thereof;

FIG. 4 is a perspective view taken from one side thereof; and

FIG. 5 is a perspective view taken from the side opposite that shown in FIG. 4.

I claim:

The ornamental design for a mobile sprayer, as shown and described.
